UNITED STATES PATENT OFFICE.

HAROLD A. ARNOLD, OF LENORA, KANSAS.

DROP-COVER CHECK.

1,425,568.

Specification of Letters Patent. Patented Aug. 15, 1922.

Application filed April 12, 1922. Serial No. 551,855.

To all whom it may concern:

Be it known that I, HAROLD A. ARNOLD, a citizen of the United States, residing at Lenora, in the county of Norton and State 5 of Kansas, have invented certain new and useful Improvements in a Drop-Cover Check, of which the following is a specification.

The present invention relates to a drop 10 cover check and has for its principal object to provide a cover supporting and checking means for retaining in open position, and checking or controlling the closing action of a top or cover for talking machines, music 15 boxes, and similar cabinets.

Another important object of the invention is to provide means of this nature which will be extremely simple and efficient in construction, reliable in operation, inexpensive to manufacture, and well adapted to the 20 purpose for which it is designed.

With the above and numerous other objects in view, the invention resides in certain novel features of construction, and the 25 combination and arrangement of parts as will be hereinafter more fully described and claimed.

In the drawing:—

Figure 1 is a vertical section through a 30 cabinet and cover therefor showing my invention attached thereto,

Figure 2 is an enlarged horizontal section taken on the line 2—2 of Figure 1 looking in the direction of the arrow,

Figure 3 is an elevation of the cylinder and associated elements,

Figure 4 is a vertical section through the cylinder, and

Figure 5 is a disassembled perspective of 40 the catch mechanism.

Referring to the drawings in detail, it will be seen that 1 designates an ordinary cover which is hinged at 2 to the cabinet 3. A supporting rod 4 is pivoted to the cover at 45 5 and its lower end passes through a horizontally disposed guide plate 6 provided with the T-shaped slot 7 and attached to the interior of the cabinet by the flange 7 extending flush with the inner face of its side 50 wall and fixed thereto by the screws 8. A check cylinder 9 is suitably mounted upon the inner face of the side wall of the cabinet 3 below the plate 6 preferably by having the crossbar 10 fixed thereto by the 55 screws 11. This cylinder 9 consists of a guide portion 12 and chambers 13 and 14,

the chamber 14 being much larger in area than the chamber 13. These chambers are separated by a partition 15 having a series of apertures 17 therein which vary in size, 60 the largest thereof being situated adjacent the top of the partition while the others progressively decrease in size, the lowest aperture being the smallest. A valve opening 18 is disposed in the bottom of the 65 chamber 13 communicating with the chamber 14 and is normally closed by a ball check valve 19. The plunger 20 is slidable through the guides 12 and into the main chamber 13. The chamber 13, when the plunger 20 70 is in a raised position is filled with oil or other liquid and as this plunger 20 is forced downwardly the oil is forced through the apertures into the larger chamber 14 and the speed with which the oil will flow from the 75 chamber 13 decreases as the plunger 20 lowers since as it passes by the apertures 17 they are closed and they grow smaller toward the bottom end. The supporting rod 4 is pivoted in the slot 22 at the upper end 80 of the plunger 20 and it will therefore be seen that the weight of the cover will tend to push the plunger downwardly in the cylinder and that the speed with which the cover initially starts will be comparatively 85 faster than that at which it will be moving as it approaches the top of the cabinet.

An inverted U-shaped frame 23 passes through the upper end of the plunger 20 and is provided with offset terminals 24 to which 90 are attached the helical springs 25 the upper ends of which are attached to the hooks 26 supported on the cross bar 27 attached to the cylinder 9 and also to the side wall of the cabinet 3. These springs 25 tend to raise 95 the inverted U-shaped member 23 and therefore tend to retard the downward movement of the plunger 20.

In order to hold the cover 1 in a raised position a check mechanism is provided 100 which consists in a pivoted locking member 29 which consists of the main bar 30 which is pivoted at 31 beneath the plate 6 and is provided with an actuating arm 32 extending at right angles thereto adjacent its 105 pivoted end and terminating in an offset apertured lip 33. The other end of the rod 30 is provided with a guide arm 34 having an arcuate slot 36 therein through which projects a pin 37 depending from the plate 110 6 whereby the pivotal movement of the member 29 is limited. A depending lip 38

is disposed on the terminal of the guide arm 34 and a spring 39 is attached thereto and fastened to the pin 40 fixed to the plate 6. As will be noted in Figure 2 this spring 39 normally retains the locking member 29 in a position whereby the bar 30 extends transversely across the auxiliary portion 42 of the T-shaped slot 7 so that the lug 43 on the supporting member 4 will rest thereon. In order to release the locking member 29, a push rod 44 is slidably mounted through an opening 45 in the front of the cabinet and a push button 46 is provided on its outer terminal.

The inner terminal thereof passes through the apertured lip 33 and a cross pin 47 is mounted adjacent this end which is adapted to engage this apertured lip 33 when the push rod is moved inwardly thereby pivoting the locking member 29 and releasing the bar 30 from engagement with the lug 43 and allowing the supporting member 4 to move downwardly because of the weight of the cover 1.

It is thought that the operation of the device will now be readily understood without a more detailed explanation and it is to be understood that numerous changes in the details of construction and in the combination and arrangement of parts may be resorted to without departing from the spirit of the invention as hereinafter claimed.

Having thus described my invention what I claim as new is:—

1. Means for checking the closing movement of a cabinet cover comprising a cylinder including a guide portion, a main chamber, an auxiliary chamber, a partition between the two chambers provided with a plurality of openings, a plunger in the cylinder movable in the main chamber, a supporting member connecting the plunger with the cover, and a catch adjacent the supporting member for engagement therewith for holding the cover in a raised position.

2. Means for checking the closing movement of a cabinet cover comprising a cylin-

der including a guide portion, a main chamber, an auxiliary chamber, a partition between the two chambers provided with a plurality of openings, a plunger in the cylinder movable in the main chamber, a supporting member connecting the plunger with the cover, and a catch adjacent the supporting member for engagement therewith for holding the cover in a raised position, means operable from the outside of the cabinet for releasing the supporting member from engagement with the catch.

3. Means for checking the closing movement of a cabinet cover comprising a cylinder, a plunger in the cylinder, a supporting member connecting the plunger with the cover, a horizontally disposed plate having a T-shaped slot therein for receiving the supporting member, a lug on the supporting member passable through the auxiliary portion of the T-shaped slot in the plate, a locking member pivoted to the plate, means for normally holding the locking member in a position so that it will engage the lug on the supporting member and hold the same in a raised position, and means operable from the outside of the cabinet for releasing said locking member from engagement with the lug so as to allow the cover to move to a closed position.

4. Means for checking the closing movement of a cabinet cover comprising a cylinder, a plunger in the cylinder, a supporting member connecting the plunger with the cover, an inverted U-shaped member attached intermediate its ends to the upper end of the plunger, springs attached to the terminals of the U-shaped member, means for supporting the other ends of the springs, and a catch adjacent the supporting member for holding it in a raised position.

In testimony whereof I affix my signature in presence of two witnesses.

HAROLD A. ARNOLD.
